GUARD FOR PAPER CUTTERS

Walter C. Eickman, Dayton, Ohio, assignor to
 Harris-Seybold-Potter Company, Cleveland,
 Ohio, a corporation of Delaware

Application December 21, 1938, Serial No. 246,965

13 Claims. (Cl. 74—615)

This invention relates to safety devices, and more particularly to a safety device or guard of the automatic type for use on a paper cutter or other machine, having a reciprocating work cutting or clamping element, or both, for protecting the machine operator against personal injury by such element or elements.

An object of my invention is to provide an improved guard device of this character which is of relatively simple and economical construction but which is efficient and reliable in operation and can be readily applied to a paper cutter or other machine of the type mentioned.

Another object is to provide a guard device whose action is very rapidly extensible so as to project itself into protective position prior to cutting or clamping of the work pile, which is a highly desirable improvement over previously built guards which advance only in direct proportion to the knife travel.

A further object is the provision of a guard which, in the retracted position, allows an unobstructed working zone and which, in the extended position, allows any work piles to be undisturbed but yet effectively prevents the operator's hands from being injured by the knife or clamp.

Yet another object of my invention is to provide an improved guard device, of the character mentioned, in which a novel arrangement of crossed links is utilized for causing automatic actuation of the guard element.

A still further object of my invention is to provide an improved guard device, of the character referred to, having a guard element arranged for positive actuation by expansible and retractable linkage and in which means adapted to be actuated in response to travel of the movable element of the machine has a push-pull connection with the linkage.

My invention may be further briefly summarized as consisting in certain novel combinations and arrangements of parts hereinafter described and particularly set out in the appended claims.

In the accompanying sheets of drawings, Fig. 1 is a partial side view of a paper cutting machine having the guard device of my invention applied thereto, showing the device partly in section and in its extended position;

Fig. 2 is another such partial side view of the machine showing the guard in its retracted position;

Fig. 3 is a partial sectional plan view taken through the guard device as indicated by line 3—3 of Fig. 2;

Fig. 4 is a plan view of the front portion of a paper cutting machine with my guard device thereon and shown in its extended position;

Fig. 5 is a partial plan view similar to that of Fig. 4, but showing the guard device in its retracted position; and

Fig. 6 is a partial front elevation looking in the direction indicated by line 6—6 of Fig. 4 and showing the thrust member or actuating cam.

Detailed reference will now be made to the drawings for the purpose of more fully describing the construction and operation of the embodiment of my invention illustrated therein. It should be understood, however, that although the drawings illustrate but one embodiment, the invention may be incorporated in various other similar devices and apparatus.

My guard device may be applied to various kinds of cutting or fabricating machines of the type having a reciprocating element and when applied to such machines, functions automatically to push the operator away from the moving element so as to prevent him from being injured thereby. By way of example, the drawings show a paper cutting machine 10 having my automatically operating guard device 11 applied thereto. This machine has an upright frame 12 with a forwardly projecting work support or table 13 thereon and an element 14 reciprocable in the frame for actuating the cutting knife or shear blade 15. The machine may also have a clamping element 15a reciprocable in the frame for applying pressure to the work pile.

The guard device itself may comprise a support 17 extending laterally across the front of the machine a suitable distance above the table 13 and a movable guard element 18 also extending laterally across the front of the machine and connected with the support by means of extensible and retractable linkage 19. The support 17 may be a bar of channel-like cross section, having its ends connected with the frame 12 adjacent the sides thereof by suitable connecting means, such as the brackets 20. The guard element 18 may be of any appropriate form, such as the laterally extending bar shown in this instance.

The linkage 19 may comprise a pair of crossed links 21 and 22 which have their inner ends pivotally connected with the support 17 as by means of the pivot pins 23 and their outer ends pivotally and slidably connected with the guard element 18 as by means of pivot pins 24 extending through longitudinal slots 25 of the guard element. The links 21 and 22 may consist of a single

bar each but, to increase the strength of the linkage, I prefer to have each link consist of a pair of vertically spaced bars, as shown in Fig. 1. The inner ends of the links may be pivotally connected 5 with the support 17 by any suitable means such as by providing the support with longitudinally spaced bosses 26 which serve as spacers for the bars of the links and through which the pivot pins 23 extend. The bars of the links may be substantially uniformly spaced from each other and 10 at the outer end of the linkage may straddle the guard element 18.

For actuating the linkage 19 to thereby project or retract the guard element 18, I provide suitable 15 actuating means which may comprise a plunger 27 extending transversely of the support 17 and a thrust element or cam 28 connected with the movable element 14 of the machine 10. Suitable bearing means may be provided on the support 17 for 20 mounting the plunger 27 thereon. For example, the support may be provided with an enlargement 29 having a bore in which the plunger 27 is slidable.

The outer end of the plunger 27 has a push-pull 25 connection with the linkage 19 so that the guard element 18 may be extended or retracted by corresponding outward and inward movements imparted to the plunger. This connection between the plunger and the linkage may be formed by 30 providing the links 21 and 22 with slots 30 adjacent their point of crossing and providing the plunger with a transverse pin 31 which extends through such slots of the links. The inner end of the plunger may be rounded and hardened and 35 thus adapted for engagement by the thrust element or cam 28.

This cam may comprise a suitably shaped and 40 constructed metal member which is mounted on the machine element 14 to project forwardly therefrom. The cam may have a relatively steeply inclined portion 32 for initial engagement with the plunger 27 to cause extension of the linkage as the knife 15 starts its downward travel and a relatively flat or slightly inclined holding 45 portion 33 for maintaining the linkage extended while the knife completes its stroke. When the movement of the machine element 14 is simply a reciprocating movement in a vertical plane, the cam 28 is mounted thereon so as to extend 50 upright, but when the machine element has a combined vertical and lateral movement, as is common in certain paper cutters and other machines, the cam may be mounted with its longitudinal axis relatively inclined, as shown in 55 Fig. 6.

For retracting the linkage and the guard element, I provide a retracting spring 35 which also acts to hold the plunger 27 in a position to be engaged by the cam 28. If desired, the plunger 60 27 may be hollow and slotted, as shown in Figs. 2 and 3, and the retracting spring 35 may be located therein. One end of the spring bears against the inner end of the plunger recess and the other end of the spring bears against a spring seat which may be in the form of a bar 36 extending through the slot of the plunger and connected with the support 17.

From the construction and arrangement of my 70 guard device, as above described, it will be seen that when the machine element 14 and the knife 15 mounted thereon move downwardly, or downwardly and laterally as the case may be, the cam 28 will engage the plunger 27 and push the same outwardly. By reason of the leverage ratio of 75 the link arms and the steeply inclined cam sur-

face, a small movement of element 14 will cause the linkage 19 to be very rapidly extended to the position shown in Fig. 4, thereby causing the guard element 18 to engage the operator's arms adjacent or above the elbows with the result that his forearms and hands are drawn away from the knife and clamp before the latter elements act upon the work pile. My safety device is preferably so constructed and arranged that when in its extended position, as shown in Figs. 1 and 10 4 the guard element 18 will be at a greater distance from the knife 15 than the length of a man's forearm. The guard is held in this extended position while the knife completes its downward stroke. When the machine element 14 is 15 lifted, the plunger 27 rides down off of the cam 28 and the spring 35 retracts the linkage and guard element 18 to the position shown in Fig. 5.

It will be noted that the support 17 and the linkage 19 are arranged on the frame 12 so that the linkage extends downwardly as well as forwardly, as is clearly indicated in Fig. 1. By reason of this relative arrangement I find that the guard element will be further removed from the table 13 when in its retracted position so as to allow the working space below to be unobstructed, and when it is extended downwardly and forwardly, its vertical clearance above the table will be slightly greater than the height of the work pile. Thus, in instances where a small 30 pile is being cut in the center portion of the table with open spaces to either side thereof creating danger zones for the operator's hands, the guard in moving to its extended position will not disturb the pile but will nevertheless sweep 35 against the arms of the operator, effectively removing his hands from said danger zone.

From the foregoing description and the accompanying drawings, it will now be readily seen that I have provided an improved automatically 40 operating guard device for paper cutters and other machines having a reciprocating element. It will be seen furthermore that this guard device, although of simple and economical construction, will be positive and reliable in operation and will effectively push the operator back 45 away from the knife on each downward stroke of the machine element. The improved linkage arrangement of my guard device provides for an extensive rapid movement of the guard element in a downward and forward direction and the push-pull actuating means cooperating with the linkage insures a smooth and positive actuation 50 of the device.

While I have illustrated and described my 55 guard device in a somewhat detailed manner, it will be understood, of course, that I do not wish to be limited to the precise arrangement of parts and details of construction herein disclosed, but regard my invention as including such changes 60 and modifications as do not constitute a departure from the spirit of the invention and the scope of the appended claims.

Having thus described my invention, I claim:

1. In a guard device for a machine having a 65 frame and a reciprocating part, a support mounted on the frame, a movable guard element in front of said reciprocating part, a pair of crossed links, a pivotal connection between said links at their intersection, a pivotal connection between one end of each link and said support and between the opposite end of each link and said guard element, one pivotal connection for each link having a fixed axis and the other two pivotal connections having movable axes, and 70 75 75

means actuated upon the movement of said reciprocating part for imparting movement to said links.

2. In a guard device for a machine having a frame and a reciprocating part, a thrust member connected with said reciprocating part for movement thereby, a support mounted on the frame, a movable guard element in front of said reciprocating part, a pair of crossed links, a pivotal connection between said links at their intersection, a pivotal connection between one end of each link and the said support and between the opposite end of each link and said guard element, one pivotal connection for each link having a fixed axis and the other two pivotal connections having movable axes, and means arranged to be engaged by said thrust member to impart movement to said links.

3. In a guard device for a machine having a frame and a reciprocating tool, a support bar extending laterally across the front of said frame and mounted thereon, a movable guard bar extending laterally in front of said supporting bar, a pair of crossed links having fixed pivotal connection with the supporting bar and movable pivotal connection with each other and with the guard bar, and means actuated upon the reciprocations of said tool for imparting movement to said links to project and retract said guard bar.

4. In a guard device for a machine having a frame and a reciprocating element, a cam connected with said reciprocating element for movement thereby, a supporting bar extending laterally at the front of said frame and mounted thereon, a movable guard bar extending laterally in front of said reciprocating element, a pair of crossed links having pivotal connection with the supporting bar and pivotal and sliding connection with the guard bar, and an actuating member shiftable transversely of the supporting bar and adapted to impart movement to the links when engaged by said cam.

5. In a guard device for a machine having a frame and a reciprocating part, a cam connected with said reciprocating part for movement thereby, a supporting element mounted on the frame, a movable guard element in front of said reciprocating part, a pair of crossed links having pivotal connection with one element and pivotal and sliding connection with the other element, and a plunger slidably mounted on said supporting element to be engaged by said cam and connected with said links adjacent their point of crossing.

6. In a guard device for a machine having a frame and a reciprocating element, a cam connected with said reciprocating element for movement thereby, a support mounted on the frame, a movable guard element in front of said reciprocating element, extensible and contractible linkage connected with the guard element for actuating the same, a plunger slidably mounted on said support to be engaged by said cam and having push-pull connection with said linkage, and means acting to retract said guard element.

7. In a guard device for a machine having a frame and a reciprocating part, a cam connected with said reciprocating part for movement thereby, a supporting element mounted on the frame, a movable guard element in front of said reciprocating part, a pair of crossed links having pivotal connection with one element and pivotal and sliding connection with the other element, a slot-screwed hollow plunger shiftable on said support and

arranged to be engaged by said cam, means providing a push-pull connection between the plunger and the links adjacent the crossing point of the latter, a retracting spring in the plunger, and means extending into the plunger through the slot thereof and providing a seat for said spring.

8. A guard device for a paper cutting machine of the type having a frame and a knife carrier movable vertically and laterally thereon, comprising a supporting bar extending across the front of the machine and connected with the frame, a guard bar extending across the machine to the front of and below said supporting bar, an inclined cam connected with the knife carrier and movable therewith, a pair of forwardly and downwardly extending crossed links having their upper ends pivoted to the supporting bar and their lower ends pivotally and slidably connected with the guard bar, and actuating means for the links including a shiftable plunger on the supporting bar and arranged to be engaged by said cam.

9. A guard device for a machine having a frame and a reciprocating element, comprising a support bar connected with the frame and extending transversely thereof, a thrust member connected with said element for movement thereby, linkage connected with said support bar arranged for projecting and retracting movement relative thereto, means on said support adapted to be engaged by said thrust member and having operative connection with the linkage for projecting and retracting the same, and a guard element connected with the linkage and actuated thereby, said support, linkage and guard element being arranged in substantially the same plane.

10. In a guard device for a machine having a frame and a reciprocating element, a thrust member connected with said reciprocating element for movement thereby, a support mounted on the frame, a movable guard element in front of said reciprocating element, and a single pair of crossed links connecting the guard element with said support and adapted to be actuated by said thrust member for imparting movement to said guard element, said links providing lever arms having a ratio such that said guard element will be extended rapidly upon small movement of said reciprocating element.

11. In a guard device for a machine having a frame and a reciprocating part, a cam connected with said reciprocating part for movement thereby, a supporting element mounted on the frame, a movable guard element in front of said reciprocating part, a pair of crossed links having pivotal connection with one element and pivotal and sliding connection with the other element, and means having connection with the links adjacent their point of crossing and adapted to be engaged by said cam, the pivotal connections between said links and elements being spaced to provide a lever arm ratio affording a relatively rapid movement for the guard element.

12. In combination with a machine having a reciprocating element, a device having a guard element and a single pair of crossed links for moving the same to a forward position, said crossed links having a pivotal interconnection so positioned relative to the ends of the links that when the device is fully extended the guard element is spaced from the reciprocating element a distance greater than the length of a normal man's forearm.

13. In a guard device for a machine having a

frame including a table portion and a reciprocating element, a thrust member connected with said reciprocating element for movement thereby, a support bar mounted on the frame and extending transversely thereof, a movable guard element in front of said reciprocating element, and crossed links connecting the guard element

with said support bar and adapted to be actuated by said thrust member for imparting movement to said guard element, said links and guard element operating in a plane extending from said support bar forwardly and downwardly with respect to said table portion. 5

WALTER C. EICKMAN.
